UNITED STATES PATENT OFFICE.

FRANK STADLER, OF AURORA, ILLINOIS.

STEAM-BOILER.

No. 804,274.

Specification of Letters Patent.

Patented Nov. 14, 1905.

Application filed June 26, 1905. Serial No. 266,991.

To all whom it may concern:

Be it known that I, FRANK STADLER, residing at Aurora, in the county of Kane and State of Illinois, have invented a new and Improved 5 Steam-Boiler, of which the following is a specification.

This invention more particularly relates to that class of upright steam-boilers having horizontal tubes, and it seeks to provide certain improvements in this type of boiler whereby to provide an economical but stable construction of boiler in which the several parts are especially designed and combined so that they can be readily separated to provide 15 for easily and expeditiously cleaning or repairing the same without the necessity of going inside thereof.

With the above and other objects in view, which will hereinafter appear, my invention 20 comprehends certain improved arrangement and detailed construction of parts, all of which will be hereinafter fully described, pointed out in the appended claims, and illustrated in the accompanying drawings, in which—

25 Figure 1 is a vertical section of an upright boiler constructed in accordance with my invention. Fig. 2 is horizontal section of the same on the line 2 2 on Fig. 1. Fig. 3 is a horizontal section on the line 3 3 on Fig. 1. 30 Fig. 4 is a similar view on the line 4 4 on Fig. 1. Fig. 5 is a detail perspective view of a portion of the upper connection of the boiler-shell, and Fig. 6 is a similar view of a portion of the lower connection of said shell. 35 Fig. 7 is a detail view of a slightly-modified form of my invention.

In the practical application of my invention the boiler shell or casing is composed of two cylindrical sections A A', the lower one, A', 40 of which is of a height sufficient to surround the fire-pot K, while the upper section incases the nest of water-tubes and extends above the same to form the upper end of the steam-space, that has the usual manhole P, as shown.

45 The bottom of the lower shell or casing section A' is securely bolted to the base or supporting member a², and its upper end is firmly riveted to a cast-steel ring C, whose horizontal portion c opposes a similar cast 50 ring C', riveted to the lower end of the upper casing or shell A, and the said rings C C' are firmly secured steam-tight by the bolt-and-nut connections D D, as shown. The bottom rim a has a vertical flange a', located inside 55 the shell A', which forms a support for the grate-bars G G of the fire-box, which is

formed in the lower end of the flue-sheet H, the lower end of which flares outwardly and is riveted to another vertical flange a³ of the bottom rim a, as at h', and the said lower end of the flue-sheet is further braced by the stay-bolts G' G', as best shown in Fig. 3.

G² designates the fuel-opening to the fire-box, and G³ the feedway, that opens through the outer shell and has the usual door G⁴. 65

S' S' designate the tubes, which are disposed in horizontal tiers and communicate with the water-space between the inner and outer shells or casings and which run crosswise of each other, whereby to form checkered fire-passages between them. (See Fig. 2.) The said flues are disposed in close relation and extend to a point near the upper or crown sheet H², which has a pendent flange h² riveted to the vertical sheet or tube-casing H, and the said 75 crown-sheet has a central outlet, to which is riveted the offtake-pipe I, that passes up through the steam-space at the upper end of the outer shell and through the collar j of a cast-metal plate J, the horizontal portion of which is secured by the bolts and nuts B to another cast-steel top member M, formed with a pendent flange m, to which the upper end of the shell or casing section A is riveted. 80

To firmly brace the tube-holding and fire-box sheet or casing at the upper end, I provide a number of brace-bars N N, the lower ends of which are detachably bolted in bifurcated blocks O O, riveted to the top or crown sheet H² and whose upper ends are bifurcated, 90 as at n n, to receive the pendent ears r of cast blocks R, bolted to the under side of the top member M. 85

While I have shown the tube sheet or casing square in horizontal section and with the 95 corners rounded, as best shown in Fig. 3, it is manifest the same may have other shapes in plan view.

From the foregoing, taken in connection with the accompanying drawings, the complete structure and its advantages will be readily apparent. By reason of arranging the parts in the manner shown and described an economical and compact but strong boiler is provided, capable of withstanding a very 105 high pressure, and by forming the casing or shell of two sections and joining them in the manner shown, taking out the bolts D, removing the nuts that secured the blocks R to the top plate M and the nuts on bolts B, the 110 entire upper section of the casing or shell can be lifted off and the tubes exposed, so they

can be readily repaired, cleaned, or removed, and the said shell or casing section A' can be quickly replaced, thus making easy to gain access to the inside of the boiler without going therein.

By arranging the flues in the manner shown and sustaining them within the shell, as stated, a maximum heating-surface is obtained in a minimum amount of space.

10 In Fig. 7 I have shown a slightly-modified form of my invention, in which rings M' M² are provided, to which the plates A and J', respectively, are riveted, as at M' M², and the rings M' M² are held together by bolts B', as 15 shown.

Having thus described my invention, what I claim, and desire to secure by Letters Patent, is—

1. A water-tube boiler comprising inner 20 and outer shells, cross-tubes mounted in the inner shell, the outer shell being formed of two sections, means for detachably joining the said two sections, a cast rim adapted to be firmly secured to a suitable base-support, 25 said rim having a vertical flange to which the lower ends of the inner and outer shells are connected, and having a second vertical flange that forms a support for the grate-bars, a top, detachably connected to the upper end of the 30 outer shell, and a gland for the offtake-flue from the crown of the inner shell, detachably connected to the said detachable outer-shell top member.

2. In a water-tube boiler of the character 35 described, in combination with the inner or tube shell, the fire-box and the offtake-flue; of an outer shell, comprising a lower fixedly-held section, an upper section detachably mounted on the lower section, a gland on the 40 offtake-flue, and a top member secured in the upper end of the outer shell and means for detachably connecting said top member to the gland as set forth.

3. In a tubular boiler of the character 45 described, the combination with the inner or tube-carrying shell, the crosswise-disposed tubes therein, the fire-pot formed in the lower end of the inner shell, and the offtake-flue that extends up centrally from the crown-

sheet of the inner shell; of the outer shell, 50 composed of an upper and a lower section, the latter being fixedly held, means for detachably connecting the upper section on the lower section, a gland or collar that surrounds the offtake-flue, a top member secured on the upper 55 end of the outer shell, means for detachably connecting said member to the collar or gland, braces secured to the top of the crown-sheet of the inner shell, and means for detachably connecting the upper end of the said braces 60 to the under side of the top member, for the purposes described.

4. A tube-boiler consisting of inner and outer shells having water-space between them, the water-tubes communicating with said space 65 and disposed in horizontal alternately-disposed tiers, the inner shell having an offtake-flue section projected from its crown and having its lower end flared outwardly, a base-rim having two upwardly-extended flanges, the 70 lower ends of the inner and outer shells being fixedly connected to the outer one of the said flanges, grate-bars mounted on the inner one of said flanges, the outer shell including an upper section, means for detachably securing 75 the upper section to the lower section, a gland on the offtake-flue, a cover-plate detachably secured to said gland and permanently secured to the upper end of the outer shell, and the braces detachably connected at their lower 80 end to the top of the crown of the inner shell and at their upper end to the under side of the cover-plate, all being arranged substantially as shown and described.

5. In a water-tube boiler of the character 85 described, in combination with the inner or tube shell, a fire-box and an offtake-flue; of an outer shell, a gland on the offtake-flue from the inner shell, a top detachably connected to the said gland and to the upper end of the 90 said tube and brace-rods whose upper ends are detachably connected to the top of the outer shell and whose lower ends are detachably connected to the top of the inner shell.

FRANK STADLER.
